UNITED STATES PATENT OFFICE.

MATTHIAS BROCK, OF BOSTON, MASSACHUSETTS, ASSIGNOR TO UNITED SHOE MACHINERY COMPANY, OF PATERSON, NEW JERSEY, A CORPORATION OF NEW JERSEY.

SHOE.

1,141,914.

Specification of Letters Patent. Patented June 1, 1915.

Continuation of application Serial No. 706,655, filed June 29, 1912. This application filed November 14, 1913. Serial No. 800,970.

To all whom it may concern:

Be it known that I, MATTHIAS BROCK, a citizen of the United States, residing at Boston, in the county of Suffolk and State 5 of Massachusetts, have invented certain Improvements in Shoes, of which the following description, in connection with the accompanying drawings, is a specification, like reference characters on the drawings indicating like parts in the several figures.

This invention relates to boots and shoes and particularly to stiffeners used in the manufacture thereof.

The invention is of particular utility as applied to heel stiffeners and will therefore be described with reference to such use.

In assembling upon a last the different parts of a shoe including a heel stiffener, a tack is usually driven through the shoe materials into the last at the rear end face of the shoe so as to fix the relation of these portions of the materials to the height of the last, and another tack is driven through the upper and stiffener into the innersole at the 25 extreme rear end of the shoe bottom. Nothing, however, is done until a later stage in the manufacture of the shoe to fasten in position the free end portions or wings of the stiffener; and it is usually found, after the 30 pulling-over operation, that these wings have been depressed and that it is necessary to pull them up into proper relation to the last bottom preparatory to the heel seat lasting operation. One reason for this condition is that the heel end face of the present-day last is vertically curved and the sides of the last are shaped to cause the shoe to hug closely the ball of the heel of the wearer's foot, particularly in the case of an Oxford

40 shoe, and manipulation of the marginal edge of the upper in the assembling and pulling-over operations tends to cause the upper and the stiffener to hug the rear end face of the last more especially at that portion adjacent 45 to the heel seat, as pointed out, for example, in United States Patent No. 855,831, granted to Emery Bayard, June 4, 1907. There is a tendency, therefore, for other portions of the stiffener at the rear end to stand somewhat away from the last and for the wings to swing downwardly or be depressed from their proper position with reference to the last bottom. It is consequently necessary as a step preparatory to heel seat lasting or as

a part of the lasting operation to pull up 55 the stiffener wings, and this operation is especially troublesome by reason of the fact that the wings in their depressed position are located between the upper and the shoe lining, which have been pulled tight in a 60 forward direction, and are therefore, difficult to reach or to grasp firmly enough to pull them up as required. This operation is usually performed by the use of hand pincers, and it is found that if the wings 65 are provided with inturned flanges which have been given a particular shape to cause them to fit the feather and lip of a welt innersole, as heretofore proposed, such use of pincers tends seriously to distort the flanges 70 from their true shape so that the shoe materials will not fit the last as closely as desired.

In the manufacture of the better grades of shoes, including most welt shoes, a straight 75 heel stiffener, *i. e.*, one the flange of which has not been molded in to lie over the heel seat of the shoe, is preferred, because such a stiffener is conformed during the lasting operation to the definite shape of the heel 80 of the last on which it is used and is of course more certain to give to the shoe the form which the pattern and last designer intended the shoe to have. In turn shoes flanged heel stiffeners cannot be used because 85 the shoe is turned inside out subsequent to the insertion of the stiffener. The wings of unflanged stiffeners, however, have a greater tendency to swing downward than do the wings of flanged stiffeners because the inwardly bent flange retards downward movement of the wings between the upper and the lining.

This invention has for an object to provide a heel stiffener which shall have substantially all the advantages of a straight 95 stiffener as above defined, and which shall have at the same time the further advantage that its wings will not swing downwardly between the upper and the lining 100 more than, if as much as, the wings of flanged stiffeners of the usual form. This object is accomplished by leaving unmolded and substantially in the vertical plane of the body of the stiffener that portion of the 105 stiffener which is to constitute the flange overlying the heel seat of the shoe, and molding into an inturned flange of any desired

shape that marginal portion of the wings which is to be located at the bottom of the shoe forwardly of the heel seat. These flanges will overlie the margin of the inner-
5 sole and retard and reduce the extent of the downward swinging of the wings of a stiffener, the main portion of which may be un-
flanged and if preferred entirely straight except for said wing ends. Any desired curva-
10 ture of form either widthwise or lengthwise may, of course, be given to the body portion of the stiffener during the molding operation, while the margin is left to be shaped precisely to the edge of the last during the
15 shoe lasting operation. With the object of avoiding injury to the stiffener through the use of hand pincers, I may also incorporate therein features of my prior invention disclosed in application Serial No.
20 787,874, filed Sept. 3, 1913, which includes the provision of pulling members on the wings of heel stiffeners, thereby providing a form of stiffener having the retaining features above noted together with ex-
25 tended portions, such as disclosed broadly in my prior application, which are located and shaped to serve as pulling members to facilitate the positioning of the wings without the danger hitherto encountered of bending the
30 stiffener flange.

To the ends above set forth the invention comprises, in its preferred embodiment, a substantially straight stiffener with or without pulling up extensions on that edge of its
35 wings which is to be located at the bottom of the shoe, which extensions if used, together with adjacent portions of the margin of the blank, are shaped by molding to include an inturned innersole feather flange
40 and an upstanding lip between which and the flange there is an abrupt bend to fit the angle between the feather and the lip of the innersole and facilitate sewing the inseam close to the base of the innersole lip.
45 The inturned feather flange retards and reduces the extent to which the wing of an otherwise unflanged stiffener will go down between the upper and the lining. The up-
turned lip, particularly if it includes the
50 pulling up extension of the stiffener blank, usually stands high enough to be seized conveniently by the operator's hand pincers and, if provided with the pulling up extension, is of such vertical extent or height, that
55 a firm hold of the stiffener wing can be obtained with the hand pincers without grasping and more or less crushing out the shape of the feather flange, as was unavoidable in using prior molded heel stiffeners because
60 the lips, when there were any, were only wide enough to sew into the inseam and were too narrow to serve as pulling up members. Said feather flange will be preferably of a width corresponding closely to the width
65 of the feather of the welt innersole with

which the stiffener is to be used and the lip will be shaped preferably to stand against the innersole rib. The excess height above the inseam due to the pulling up extension may, of course, be cut off in the inseam trimming operation. The stiffener will thus have important advantages, particularly as contributing to high grade heel seat lasting for which straight heel stiffeners are generally used, and also to the formation of a tight
70 and properly located welt attaching seam, and, by reason of the height of the extensions on its lips the stiffener will be shaped also to facilitate the proper positioning of the stiffener wings without liability of distorting materially the molded portions of the stiffener.
75

This application is to be regarded, further, as a continuation of my earlier and co-pending application for patent on improvements in lasting machines, Ser. No. 706,655, filed June 29, 1912, in so far as relates to subject matter common to the two applications.
80

The invention will be understood more readily by reference to the accompanying drawings, in which—

Figure 1 is a perspective view of a preferred form of heel stiffener embodying the invention, Fig. 2 shows the stiffener of Fig. 95 1 partially molded to the shape of the heel portion of a shoe, Fig. 3 illustrates the use of the stiffener in the manufacture of a welt shoe.

The stiffener as a whole, which is design-
100 nated by the numeral 2, may either have the simple uncurved form illustrated in Fig. 1 or may be molded into some suitable heel shape as, for example, that shown in Fig. 2 prior to its use in the assembling operation.
105 The upper portion of the stiffener, as viewed in these figures, is that portion which will be located at or adjacent to the bottom of the assembled shoe, and it will be understood that the two opposite end portions of the stiffener constitute the wings which will extend forwardly along the heel into the shank. The stiffener presents an edge 4 of regular contour of a length to extend from the rear of the heel substantially to the heel
110 breast location on each side and is shaped to provide for the formation during the lasting operation of an inturned flange of substantially uniform width to overlie the edges of the heel seat in the lasted shoe, the approximate line on which the stiffener will be turned down to form this flange being indicated by the dotted line 6 in Fig. 1.
115 Running from the ends of the intermediate edge portion 4 the edge of the stiffener is provided with shaped or molded portions each comprising a downturned flange 8 and an upstanding lip 10. The flange 8 is intended to lie upon the feather of a welt innersole and is preferably of a width cor-
120
125
130

responding to the width of the feather so that the lip 10 may stand against the innersole rib and facilitate the formation of a tight welt attaching seam by making it 5 easy for the needle of the sewing mechanism to enter the lip and fasten the upper stock in the angle close to the base of the lip. The desired relation of the parts is illustrated in Fig. 3, where the feather and the rib of the 10 innersole are indicated respectively by the numerals 12 and 14. This figure shows the parts of the shoe in their assembled relation, with the stiffener 2 located between the lining 16 and the upper 18 and the upper 15 materials secured temporarily to the innersole at the rear of the heel seat by a tack 20. In Fig. 3 the stiffener wings are shown as located in their proper position preparatory to the heel seat lasting operation. As 20 already pointed out, however, these wings are usually found, after the pulling-over operation, to be somewhat out of position so that they must be pulled into their proper relation to the innersole. In order to facilitate 25 this operation the lips 10 are, by a feature of the present invention, suitably extended widthwise of the stiffener, *i. e.*, upwardly as the stiffener is viewed in the drawings, to constitute pulling members 30 which will project within convenient reach of the operator for pulling the stiffener wings when the inturned flanges 8 do not entirely prevent the wings from getting down between the upper and the lining. As 35 shown in Fig. 1 these lips are formed to include portions of the material of the stiffener which, prior to the molding of the ends, form offsets or extensions of any desired extent from the regular edge portion 40 4, the dotted lines 22 in this figure indicating the shape of the stiffener ends before the molding of the flanges and lips, a blank substantially of this shape forming the subject-matter of my prior application Ser. No. 45 787,874, previously mentioned. The dotted line 6 which indicates the prospective boundary of the heel seat flange forms, it will be noted, a continuation of the boundary of the flanges 8; and since the width of the 50 flange 8, corresponding to the width of the feather of the innersole, is usually less than the width of the heel seat flange of the stiffener, it follows that the width of the lip 10 is as great as, or greater than, the width 55 of the offset or extension from the edge 4, and that the combined width of the flange 8 and the lip 10 is much greater than the width of that portion of the blank which is to be turned down to form the heel seat flange. In consequence of this construction 60 the lips 10 are suitably extended to project within convenient reach of the operator when the ends of the stiffener are depressed and to serve as pulling members which may 65 be readily grasped to bring the stiffener ends to their proper position. It will be seen also that where pincers are employed an adequate hold can be obtained on the lips 10 without reaching downward far enough to seize and crush the flange 8, and the 70 straight upward pull upon these lip portions will not injuriously distort the stiffener so as to detract materially from its fitting qualities in the shoe.

It will be understood that the form and dimensions of the different parts of the stiffener above described may be suitably varied to conform to different conditions or requirements, and such variations are comprehended within the scope of the invention. 75

Having described the invention, what I claim as new and desire to secure by Letters Patent of the United States is:—

1. A heel stiffener having its edge upright and in substantially the vertical plane of its body portion around the heel seat and molded to present inturned flanges shaped to the feather of the innersole in front of the heel breast. 80
2. A heel stiffener of substantially straight formation widthwise and having upon its end portions, on the edge which is to be located at the bottom of the shoe, molded flanges shaped to overlie a portion of the innersole. 85
3. A heel stiffener having, on the edge which is to overlie the innersole in the shoe, molded portions running from the shank ends backwardly a short distance and each comprising an inturned flange and an up-standing lip which terminates at a point remote from that portion of the stiffener which is to be located at the rear of the heel, said lips including widthwise extensions of said stiffener to constitute pulling members to be engaged for positioning the stiffener ends in the lasting operation. 90
4. A heel stiffener having that portion which is to be located at the bottom of the shoe formed with an edge of substantially regular contour of a length to extend around the heel from a position at or near the breast line on one side to a similar position on the other side, and molded portions running from said regular edge portion toward the ends of the stiffener and each comprising an inturned flange and an upstanding lip, said lips forming offsets or extensions from said regular edge portion of the stiffener to constitute pulling members to be engaged for positioning the stiffener ends in the lasting operation. 95
5. A heel stiffener having on that edge which is to be located at the bottom of the shoe molded portions adjacent to the ends of the stiffener and each comprising an in-turned flange of a width to overlie the feather of the innersole and an upstanding lip adapted to stand adjacent to the innersole rib, said lips including widthwise ex- 100
6. A heel stiffener having on that edge which is to be located at the bottom of the shoe a flange of a width to overlie the feather of the innersole and an upstanding lip adapted to stand adjacent to the innersole rib, said flange including widthwise ex- 105
7. A heel stiffener having on that edge which is to be located at the bottom of the shoe a flange of a width to overlie the feather of the innersole and an upstanding lip adapted to stand adjacent to the innersole rib, said flange including widthwise ex- 110
8. A heel stiffener having on that edge which is to be located at the bottom of the shoe a flange of a width to overlie the feather of the innersole and an upstanding lip adapted to stand adjacent to the innersole rib, said flange including widthwise ex- 115
9. A heel stiffener having on that edge which is to be located at the bottom of the shoe a flange of a width to overlie the feather of the innersole and an upstanding lip adapted to stand adjacent to the innersole rib, said flange including widthwise ex- 120
10. A heel stiffener having on that edge which is to be located at the bottom of the shoe a flange of a width to overlie the feather of the innersole and an upstanding lip adapted to stand adjacent to the innersole rib, said flange including widthwise ex- 125
11. A heel stiffener having on that edge which is to be located at the bottom of the shoe a flange of a width to overlie the feather of the innersole and an upstanding lip adapted to stand adjacent to the innersole rib, said flange including widthwise ex- 130

tensions of the stiffener which terminate at points remote from that portion of the stiffener which is to be located at the rear of the heel and are formed to serve as pulling members to be engaged for positioning the stiffener ends in the lasting operation.

6. A heel stiffener having that edge portion which is to be located at the bottom of the shoe adapted to be turned down to form 10 a flange of substantially uniform width overlying the edges of the heel seat forwardly to a point on each side at or adjacent to the heel breast location, and molded portions adapted to extend forwardly into the 15 shank of the shoe and each comprising an inturned flange and an upstanding lip, the combined width of said flange and lip being greater than the width of that portion of the blank which is to be turned down to 20 form the flange upon the heel seat.

7. A heel stiffener having formed on one edge adjacent to an end of the stiffener a molded portion comprising an inturned flange shaped to lie upon the feather of an innersole and an upstanding lip located to 25 stand adjacent to the innersole rib, said lip including a widthwise extension of the stiffener which terminates at a point remote from that portion of the stiffener which is to be located at the rear of the heel and is 30 adapted to serve as a pulling member to be engaged for positioning the stiffener end in the lasting operation.

In testimony whereof I have signed my name to this specification in the presence of 35 two subscribing witnesses.

MATTHIAS BROCK.
